UNITED STATES PATENT OFFICE.

JAMES H. DENNEDY, OF DETROIT, MICHIGAN.

ELECTRIC SWITCH.

Application filed June 29, 1922. Serial No. 571,881.

To all whom it may concern:

Be it known that I, JAMES H. DENNEDY, a citizen of the United States, residing at Detroit, county of Wayne, State of Michigan, have invented a certain new and useful improvement in Electric Switches, and declare the following to be a full, clear, and exact description of the same, such as will enable others skilled in the art to which it pertains to make and use the same, reference being had to the accompanying drawings, which form a part of this specification.

This invention relates to electric switches which may be operated either manually or automatically as desired and the object of the invention is to provide a switch mechanism comprising a pair of contact members of the knife type which may be quickly turned to make or break a circuit and thus prevent the drawing of an arc. Another object of the invention is to provide a switch which is very simple and positive in action and in which a very slight movement of the control member is required to actuate the switch. Another object of the invention is to provide a switch in which the contact members are moved slowly throughout a part of their travel and through the remainder of the travel are moved very quickly. This quick movement of the switch members is accomplished by means of a series of levers and a spring so that when the levers are moved to a certain point by the actuating member the spring takes effect to quickly throw the contact members to make or break the circuit. These objects and the several novel features of the invention are hereinafter more fully described and claimed and the preferred form of construction by which these objects are attained is shown in the accompanying drawings in which—

Fig. 1 is a plan view of an electric switch embodying my invention.

Fig. 2 is a side elevation showing the switch in the closed position.

Fig. 3 is a view similar to Fig. 2 showing the switch in the open position.

Fig. 4 is a view showing the switch connected to an automatic operating device therefor.

As shown in the drawings the switch comprises a base 1 on which is mounted a frame comprising side plates 2 and 3 as will be seen more particularly in Fig. 1. A shaft 4 extends through the two frame members 2 and 3 at one end and pivoted on the outer sides of these frame members on the shaft 4 is a pair of contact members 5 each formed at the rear end with outturned flanges 6 and 7 in V form and also with terminal upturned lugs 8 and 9. The end 10 of each contact member 5 is adapted for engagement with the respective spring contact 11 or 12 as the case may be there being two members 5 and a contact member 11 or 12 for the respective member. A circuit consisting of the lines 13 and 14 is connected with these contacts 11 and 12 as shown in Fig. 1 and when the ends 10 of the contact members 5 are passed between the blades of the contacts 11 and 12 the circuit is completed by passing through a bracket 15 connecting the said members 5. The levers 5 are operated by a U shaped actuator member 16 pivotally mounted on a shaft 17 extending through the two frame members 2 and 3 and the ends of legs 18 of this member 16 extend between the flanges 6 and 7 and lugs 8 and 9 of the members 5. The cross member of the U connecting the legs thereof is provided with an aperture through which the end of a pin 19 extends; the said pin being pivotally mounted at 20 on a lever 21 which is pivotally mounted on the shaft 4. A coiled spring 22 extends about the pin 19 and between the shank of the pin and the bar of the U shaped member 16. The lever 21 is pivoted to the shaft 4 between the side frames, the lever 21 being formed of two duplicate parts as will be seen from Fig. 1 and the head of the pin 19 extends between the adjacent ends of the two parts of the lever 21 as will be readily understood. Near the pivot point of the lever 21 is a shaft 23 connecting the two parts of the lever 21 and pivotally mounted on this shaft and extending downwardly therefrom, as shown in Fig. 2, is a link 24 which is pivotally connected at 25 with a link 26 which in turn is pivoted on a shaft 27 mounted in the frame members. There

are preferably two links 26 and supported therebetween is a shaft 29 on which is pivotally mounted a threaded stud shaft 30. The two part lever 21 above mentioned is provided with an arcuate slot 31 near the end on which the pin 19 is pivoted and the shaft 17 extends through this slot and limits the movement of the lever 21 on its pivot. For manual operation an insulating knob 10 is threaded onto the shaft 30 and when the switch is in the normal open position shown in Fig. 3 the knob and shaft 30 may be forced upwardly to close the switch. This upward movement of the shaft 30 raises the lever 26 on the pivot 27 thus raising the link 24 which raises the lever 21 on its pivot 4 thus raising the pivot 20 of the pin 19 upwardly and compressing the spring 22 and, as this pivot point 20 passes the center line of the 20 U shaped member 16 the spring will act to depress the outer end of the member 16 and raise the opposite ends 18 on the pivot 17. Due to the lug 8 and flange 6 the ends 18 of the member 16 by engaging first against 25 the lugs 8 begin to turn the members 5 and then engages the flanges 6 comparatively close to the pivot point of the contact members 5 which causes a quick movement of the ends 10 in engaging the contacts 27 and 28. This action of the ends 18 of the U shaped 30 member 16 in relation to the contact members 5 is the same either in the upward or downward movement the lugs 9 and flanges 7 being engaged by the legs 18 on downward movement thereof. This device may be utilized with an artificial refrigerating system in which a compressor operates in conjunction with a circulating system having a high and low pressure side. In this 40 case the device shown in Fig. 4 is connected to the low pressure line 32 by means of a coupling 33. The switch in this case controls the electric motor for operating the compressor. The switch is shown in Fig. 4 in the open position at which time the motor and compressor are not operating but upon a slight pressure being produced in the line 32 the shaft 34 is raised which is 45 connected by means of a turn buckle 35 to the threaded shaft 30 of the switch which extends through an aperture 36 provided in the switch base as shown in Fig. 1. Upon upward movement of the shaft 34 the switch is thrown to the closed position shown in 50 Fig. 2 as will be readily understood which starts the motor and compressor and as the pressure is reduced in the line 32 the coiled spring 37 forces the shaft 34 downwardly which draws the rod 30 downwardly and 55 opens the switch as shown in Fig. 3. As this device for automatically operating the switch is applied for in another application I have merely pointed out the principal parts by which the switch may be auto-

matically operated, this application being 65 limited to the switch structure and, as there are many devices for automatically operating a switch I do not wish to limit the use of this switch to only one operating device.

From the foregoing description it becomes 70 evident that the device is very simple and efficient in operation, will not easily get out of order, is actuated quickly and positively and provides a device which accomplishes the objects described.

Having thus fully described my invention, its utility and mode of operation, what I claim and desire to secure by Letters Patent of the United States is—

1. In an electric switch, a base of insulating material, a pair of spring contacts mounted on the base, a pair of frame members mounted on the base, a pair of contact members pivotally mounted at one end of the frame members and adapted to engage 85 the spring contacts, the said contact members being each provided with outturned flanges arranged in substantially V shaped form, a U shaped actuator member pivoted at the opposite end of the frame member, 90 the legs of the U shaped actuator extending between the flanges of the respective contact member, a pair of outturned lugs on each contact member, the legs of the U shaped actuator during movement from one position to the other being adapted to first engage 95 the respective lug intermediate the end and the pivot point of the respective leg and then engage the flange near the pivot point of the contact member, and means for actuating the said actuator.

2. In an electric switch, a base, a pair of frame members mounted thereon, a U shaped actuator pivotally mounted intermediate its ends at one end of the frame members, a 105 pair of contact members actuatable by the extending ends of the U shaped actuator, a pair of contacts mounted on the base and adapted to receive the contact members, a lever pivotally mounted at the end of the 110 frame opposite the actuator, the end of the said lever extending between the legs of the U shaped actuator, and between the end and pivot point thereof, a pin pivotally connected to the end of the said lever and extending through an aperture provided therefor in the end of the said actuator, a 115 coiled spring about the said pin engaging the end of the actuator and exerting pressure thereagainst and means for moving the 120 said lever on its pivot.

3. In an electric switch, a base of insulating material, a pair of frame members mounted thereon, a U shaped actuator pivotally mounted intermediate its ends at one end of the frame members, a pair of contact members pivotally mounted on the frame members at the end opposite the

- actuator, a pair of contacts on the base for receiving the ends of the contact members, each contact member being provided with outturned flanges in substantially V shape 5 between which the legs of the U shaped actuator engage, a lever pivotally mounted between the frame members, the free end of the said lever extending between the legs of the U shaped actuator, a spring member 10 pivotally connected to the end of the said lever and engaging the actuator member, and means limiting upward or downward movement of the said lever on its pivot, the arrangement being such that upward movement of the lever moves the pivot point for the spring member above the pivot of the U shaped actuator and downward movement of the lever moves the pivot point of the spring member below the pivot of the 15 actuator.
4. In an electric switch, a base of insulating material, a pair of frame members mounted thereon, a U-shaped actuator pivotally mounted intermediate its ends at one 20 end of the frame members, a pair of contact members pivotally mounted at the opposite ends of the frame members and actuatable simultaneously by the legs of the U-shaped actuator, a pair of contacts 25 mounted on the base and adapted to receive the contact members, a lever pivotally mounted in the end of the frame members opposite the actuator, the end of the lever extending within the U shaped actuator and 30 yieldable means connecting the lever and actuator whereby upward movement of the lever throws the actuator to close the switch and downward movement of the lever throws the actuator to open the switch.
5. In an electric switch, a base of insulating material, a contact mounted thereon, a frame member mounted on the base, a contact member pivotally mounted on the frame member and adapted to engage the contact 35 of the base, the said contact member being provided with outturned flanges extending at an angle one to the other, an actuator member pivoted at the opposite end of the frame member having an end extending between the flanges of the contact member, means for turning the actuator member on its pivot, and a pair of lugs on the contact member between which the actuator member extends, the actuator member engaging the 40 respective lug between the end and pivot point of the actuator during a portion of its movement and the end of the actuator engaging the respective flange near the pivot point of the contact member during the remainder of its movement.
6. In an electric switch, the combination with a circuit having a terminal, a pivoted contact lever adapted to be turned to engage or disengage the terminal, a pivoted 45 actuator lever for the contact lever, said contact lever having two parts on each side thereof extending over opposite sides of the actuator, the arrangement being such that movement of the actuator in either direction on its pivot first engages a part nearest its pivot to turn the contact lever and thereafter engages a part most distant from its pivot to finally and more rapidly turn the contact lever on its pivot.
7. In an electric switch, the combination 50 with a circuit having a terminal, a pivoted contact lever adapted to be turned to engage or disengage the terminal, a pivoted actuator lever for the contact lever, said contact lever having two parts on each side 55 thereof extending over opposite sides of the actuator, the arrangement being such that movement of the actuator in either direction on its pivot first engages a part nearest its pivot to turn the contact lever and thereafter engages a part most distant from its pivot to finally and more rapidly turn the contact lever on its pivot, and a spring released to action to turn the actuator before it engages the portion of the contact lever 60 most distant from its pivot, and thereby complete movement of the contact member from its pivot.
8. In an electric switch, the combination 65 with a circuit having a terminal contact, a pivoted contact lever adapted to be turned to engage or disengage the contact terminal and a pivoted actuator lever for movement of the contact lever, said actuator lever in its movement on its pivot in either direction first engaging a portion of the contact lever at a point remote from its pivot to cause initial movement of the contact lever and finally to engage a portion of the contact lever at a point near its pivot to increase 70 the speed of movement thereof, and a spring released to actuation of the actuator at about the time of contact thereof with the point of the contact lever nearest its pivot.
9. In a switch for an electric circuit, a contact lever, an actuator lever for moving the contact lever to make or break the circuit, the actuator lever being insulated from the circuit, said contact lever being arranged with two parts for engagement by the actuator, one of said parts being near the pivot point of the actuator and the other a 75 distance therefrom whereby movement of the actuator lever first exerts comparatively great power in movement of the contact member and then by engagement with the part distant from its pivot moves the contact lever with comparatively great speed, the two levers being so arranged as to prevent the parts moving out of relationship.
10. An electric switch comprising a terminal contact, a contact lever moving to engage and disengage the terminal contact,

an actuator lever for moving the contact lever, said actuator lever in its movement to disengage the contact lever from the terminal contact, first engaging the contact lever with more powerful leverage to cause the initial movement of the contact lever and thereafter engaging the contact lever with a less powerful leverage to accelerate the

movement of the lever as it finally breaks contact with the terminal contact, said actuator lever locking said contact lever in its final open position. 16

In testimony whereof, I sign this specification.

JAMES H. DENNEDY.
